H. A. CARSTENS

COOLING DEVICE

Filed April 11, 1922

Inventor
H. A. Carstens
by Orwig & Hague, Atty.

UNITED STATES PATENT OFFICE.

HENRY A. CARSTENS, OF ACKLEY, IOWA.

COOLING DEVICE.

Application filed April 11, 1922. Serial No. 551,512.

To all whom it may concern:

Be it known that I, HENRY A. CARSTENS, a citizen of the United States, and resident of Ackley, in the county of Hardin and State of Iowa, have invented a certain new and useful Cooling Device, of which the following is a specification.

The object of my invention is to provide a refrigerating apparatus for domestic use of simple, durable and inexpensive construction that may be readily, and easily installed in a home, and which will preserve food for a maximum length of time and in good condition without the use of ice.

15 My device relates to that class of cold storage devices in which a tube is extended some distance down in the ground and the dumb waiter is placed therein and designed to be elevated above the tube so that access 20 may be had to the contents and then lowered to the bottom of the tube where the cold air settles by gravity and the temperature is lowered by evaporation of the water of condensation.

25 More specifically it is my object to provide a device of this class in which the act of raising and lowering the dumb waiter into the tube will remove the foul air that has settled in the bottom of the tube, and 30 replace it with fresh air from above and without raising the temperature of the air at the bottom of the tube to any appreciable extent, and

35 Further, to provide a device of this class in which the evaporation of the water of condensation is facilitated to lower the temperature, and also to provide a device of this class in which the water of condensation in normal quantities will not affect the 40 circulation of the air.

45 My invention consists in the construction, arrangement and combination of the various parts of the device, whereby the objects contemplated are attained, as hereinafter more fully set forth, pointed out in my claim and illustrated in the accompanying drawings, in which:

Figure 1 shows a front elevation of the complete apparatus embodying my invention with parts broken away to show structural details.

50 Figure 2 shows a sectional view on the line 2—2 of Figure 1, and

55 Figure 3 shows a sectional view on the line 3—3 of Figure 2.

Referring to the accompanying drawings,

I have used the reference numeral 10 to indicate a tube made water tight, opened at its top and closed at its bottom, and designed to be inserted to a considerable distance into the ground. At the top of the tube there is an enclosed box 11 having a door 12 at the front. The interior of this box communicates with the open upper end of the tube and this opening is normally covered by a removable cover 13 which may be moved from position at the top of the tube upwardly inside of the box 11.

Arranged along side of the tube 10 is a weight tube 14 of substantially the same length as the tube 10, and the weight tube is extended upwardly into the interior of the box 11 above its bottom. Mounted within the tube 10 is a dumb waiter 15 of ordinary construction which loosely fits the interior of the tube so that it may be readily moved up and down, and connected to the dumb waiter is a cable 16 which extends upwardly and passes through the cover 13 and around the pulleys 17 and then downwardly where it is attached to a weight 18 which substantially counter-balances the weight of the dumb waiter.

Attached to one of the pulleys 17 is a crank 19 by which the pulleys may be operated from the exterior of the box 11 to move the dumb waiter up and down. Arranged adjacent to the exterior of the tube 10 is a ventilating tube 20, the upper end of which opens flush with the bottom of the interior of the box 11, and the lower end at 21 is provided with an elbow and opens into the tube 10 at a point spaced above the bottom thereof, as shown in Figure 3.

In practical operation and assuming that it is desired to place food in the dumb waiter and that the dumb waiter is at its upper limit of movement, then the door 12 is opened and the food is placed in position and then the door is closed and the crank 19 manipulated to lower the dumb waiter to position near the bottom of the tube where the food will be preserved during hot weather because of the accumulation of cold air at the bottom of the tube and under the surface of the ground.

If the dumb waiter has been left at the bottom of the tube for a period of time and assuming that it is desired to remove food from it, the operator manipulates the crank 19 and elevates the dumb waiter to a readily

accessible position inside of the box 11, and when it is elevated the door 12 is opened. During this operation partially cool air from the interior of the box 11 is drawn 5 down through the ventilating tube and fills the lower interior of the tube 10, and when the dumb waiter is again lowered the door 12 may be left open and when this is done the air from the bottom of the tube 10 is 10 forced outwardly through the ventilating tube and to a point exterior to the box 11, so that any foul or tainted air in the bottom of the tube will be discharged to the outside atmosphere, and in the event that it should 15 be found that there is a considerable amount of foul or tainted air it can be "pumped out" by simply raising and lowering the dumb waiter while the door 12 is open, and if desired, the door 12 may be left closed 20 and then the temperature of the interior of the apparatus is not increased by the raising and lowering of the dumb waiter. As the dumb waiter ascends the cool air is forced into the box 11 and when the dumb waiter 25 descends cool air from the interior of the box 11 would be drawn down to the bottom of the tube 10.

In devices of this kind there is during 30 warm weather a considerable accumulation of water of condensation in the bottom of the tube and the evaporation of this water adds materially in this cooling process. However, by my improved arrangement this 35 water of condensation will not retard the circulation of air which will pass over the top of the body of water and by its move-

ment facilitate the evaporation and consequent cooling.

I claim as my invention:

A cooling device comprising a tube open at 40 its top and closed at the bottom, and designed to be inserted in the ground, a box at the top of the tube and in communication therewith, said box being substantially air tight and provided on one side with a door opening, a door for closing said door opening, a dumb waiter mounted within the tube and capable of moving from position within the box to position at the lower end of the tube, a counterbalancing weight for the dumb 45 waiter, a tube parallel with the main tube for receiving said counterbalancing weight, said weight being fitted within the tube loosely so that air may freely pass around it, and a ventilating tube arranged exterior to 50 the main tube and having its upper end open within the interior of the box at the bottom thereof and having its lower end communicating with the bottom portion of the tube at a point spaced above the bottom 55 thereof, said ventilating tube being open and unobstructed so that when the dumb waiter descends, air within the bottom of the main tube may pass freely up through said ventilating tube into the box at the top, 60 and as the dumb waiter is being elevated, air within the box may freely pass to the bottom of the tube, substantially as and for the purposes stated.

Des Moines, Iowa, March 16, 1922.

HENRY A. CARSTENS.
